Atty.

UNITED STATES PATENT OFFICE.

SAMUEL HEATH, OF ROXBOROUGH, PENNSYLVANIA.

COMBUSTIBLE SMOKELESS GAS AND AIR CHAMBER FOR GAS-BURNERS.

1,295,318.

Specification of Letters Patent. Patented Feb. 25, 1919.

Application filed December 2, 1918. Serial No. 264,905.

To all whom it may concern:

Be it known that I, SAMUEL HEATH, a citizen of the United States, residing at Roxborough, in the county of Philadelphia and State of Pennsylvania, have invented new and useful Improvements in Combustible Smokeless Gas and Air Chambers for Gas-Burners, of which the following is a specification.

10 My invention relates to new and useful improvements in combustible smokeless air and gas chamber for gas burners, and has for its object to provide an exceedingly simple and effective device of this character which may be readily and quickly applied to a gas burner so as to produce about said burner an air chamber to which air passes at a point below the burner tip or the flame issuing therefrom when the burner is lighted so that said air will be preheated and caused to flow directly into the flame thereby producing a much larger flame and of course a much brighter light without any additional flow of gas and at the same time the disagreeable odor and smoke will be eliminated.

15 A further object of the invention is to provide a device of the character described which may be frictionally mounted upon a gas burner of any ordinary or well known construction used for lighting purposes and which will so mix the necessary amount of air at the point of combustion thereby reducing the consumption of gas or increasing 20 the size and brightness of the flame issuing from the burner.

25 A still further object of the invention is to provide a device of this character which will cause air to be injected into a flame whereby sufficient oxygen is supplied to create a perfect combustion so that the particles of unburned substances which will throw off as smoke will be consumed which will eliminate disagreeable odors and which will prevent soiled ceilings or wall papers.

30 The device is designed to be constructed of either one or two parts so that it will be inexpensive in the cost of manufacture, will have no parts to get out of order and which 35 may be readily and quickly placed in position and adjusted to give the desired size of flame or brightness of light.

With these ends in view this invention consists in the details of construction and 40 combination of elements hereinafter set

forth and then specifically designated by the claims.

In order that those skilled in the art to which this invention appertains may understand how to make and use the same, I will 45 describe its construction in detail referring by numerals to the accompanying drawings forming a part of this application, in which—

Figure 1, is a side elevation of my improved combustible smokeless air and gas chamber for gas burners showing it applied to a gas burner.

Fig. 2, is a vertical sectional view thereof, the burner being in elevation.

Fig. 3, is a similar view of a slightly modified form of my invention, the same being removed from the burner.

Fig. 4, is a side elevation of the nipple used in the construction illustrated in Fig. 3.

Fig. 5, is a side elevation of a still further modified form of my invention.

Fig. 6, is a plan view of Fig. 1, and

Fig. 7, is an enlarged section at the line 7—7 of Fig. 1.

In carrying out my invention as here embodied 2 represents a gas burner of any well known construction and of any desirable size and shape, the one here illustrated being the same as is commonly used for supplying 50 light and this burner is provided with a slotted tip 3.

On this burner is adjustably and slidably mounted my improved combustible smokeless air and gas chamber for gas burners 4 55 which as shown in Figs. 1 and 2 consists of a body 5 of any desirable shape, size or configuration to snugly fit about a portion of the gas burner in order that the same will frictionally engage said gas burner so that the 60 device may be adjusted vertically or longitudinally thereon and which will remain in its adjusted position by the frictional contact thereof with the burner. From the body projects an enlarged portion or bowl 6 which may be of any desirable configuration or design and which might enhance the 65 value of the device from the standpoint of beauty.

Above the bowl will form air inlets 7 70 which may be produced by cutting the metal away to leave a number of spaced ribs 8 with large opening therebetween as shown in Figs. 1 and 2 or the metal from which the device is produced may be perforated as 75

- shown at 9 in Fig. 5 and above these air inlets is located a head 10 which is spaced from the gas burner and its tip to produce an air chamber 11 and this head is provided with an annular projection or flange 12 formed in some suitable manner as by producing an outwardly projecting concavo-convex ridge and the extreme upper end of said head is flared outward as indicated at 10 13 which becomes a guide for the flame issuing from the burner.

In Figs. 3 and 4 I have shown another form of my invention in which the main portion is an exact duplicate of that shown in Figs. 1 and 2, but to this latter device is added a thimble 14 which is adapted to be placed in the outer or supporting part of my invention from its upper end and this thimble is of sufficient length to be disposed entirely across the air inlets 7 and that portion so disposed across the inlets is perforated as at 15 while the upper end is flared outward as at 16 after the manner of the mouth of a bell and this flared portion is adapted to approximately coincide with the flared portion 13 of the outer part of my device so as to support the thimble and properly position the same and when in use this thimble is spaced from the gas burner 2 in the same manner as the head 10 so that an air chamber is formed about said gas burner.

In Fig. 5, the device shown is the same as that illustrated in Figs. 1 and 2 with the exception that that portion thereof between the bowl 6 and the head 10 is perforated as before stated to provide the necessary air inlets communicating with the air chamber 11.

40 In practice the device is placed upon a gas burner as shown in Figs. 1 and 2 and the same adjusted vertically or longitudinally of the gas burner in order that the head thereof will be in the proper position relative to the burner tip 3 for supplying the necessary air and causing the same to flow into the flame at the point of combustion. After the proper adjustment has been obtained the air will flow into the air inlets 7 because of the draft induced by the flame issuing from the burner and as this air flows into the air chamber 11 it will be raised in temperature by its contact with the walls of the head 10 so that when mixed with the flame a necessary amount of preheated oxygen is supplied to cause the ordinary non-combustible materials to be consumed thereby eliminating smoke and disagreeable odors.

In actual practice it has been found that 60 by forming a flange or ridge 12 about the head just above the air inlet openings much better results are obtained and presumably this ridge acts as a baffle and produces the

air eddies or currents which causes a greater amount of air to flow through the air inlets 65 than would be the case if no ridge or flange were provided.

Of course I do not wish to be limited to the exact details of construction as herein shown as these may be limited within the 70 limits of the appended claims without departing from the spirit of my invention.

Having thus fully described my invention what I claim as new and patentable is:—

1. In a device of the character stated a 75 body adapted to frictionally engage a gas burner, a bowl projecting therefrom, spaced ribs formed integral with said bowl and forming air inlets therebetween, a head carried by said ribs of a greater diameter than 80 the burner on which it is mounted thereby producing an air chamber with which the air inlets communicate, said air chamber being opened at its upper end, the upper end of said head being flared outward and a concavo-convex annular ridge formed on the exterior of said head upon the inlet openings.

2. In a device of the character stated a 90 body adapted to frictionally engage a gas burner, a bowl projecting therefrom, spaced ribs formed integral with said bowl and forming air inlets therebetween, a head carried by said ribs of a greater diameter than 95 the burner on which it is mounted thereby producing an air chamber with which the air inlets communicate, said air chamber being opened at its upper end, the upper end of said head being flared outward, a concavo-convex annular ridge formed on the 100 exterior of said head upon the inlet openings and a thimble having a flared end adapted to be placed in the head and extended into the bowl so as to be disposed across the air inlets, said thimble having a flared end for positioning the same and provided with perforations to produce air inlets leading to the air chamber.

3. In a device of the character stated a 110 body adapted to snugly fit about a gas burner, an integral bowl formed therewith, an integral perforated portion projecting therefrom of greater diameter than the burner on which it is placed, an integral head formed with said perforated portion 115 also of greater diameter on which the device is placed to produce an air chamber, the perforations in the perforated portion forming the air inlets to said chamber, the upper end of said head being flared outwardly and an exterior annular ridge projecting from said head.

In testimony whereof, I have hereunto affixed my signature.

SAMUEL HEATH.
